UNITED STATES PATENT OFFICE.

SAMUEL STRAUSS, OF LOS ANGELES, CALIFORNIA.

METHOD OF MAKING SHOES.

1,325,764.

Specification of Letters Patent. Patented Dec. 23, 1919.

Application filed February 21, 1917, Serial No. 150,031. Renewed May 7, 1919. Serial No. 295,453.

To all whom it may concern:

Be it known that I, SAMUEL STRAUSS, a citizen of the United States, residing at Los Angeles, in the county of Los Angeles 5 and State of California, have invented a new and useful Method of Making Shoes, of which the following is a specification.

An object of this invention is to minimize the cost of shoes made of leather or 10 similar material.

Another object is to produce an absolutely seamless one-piece leather shoe, thereby insuring comfort to the wearer thereof.

Another object is the production of a 15 leather shoe having any desired shape and style.

Other objects and advantages will appear in the subjoined detail description.

The accompanying drawings illustrate the 20 invention:

Figure 1 is a vertical mid section of a machine well adapted to manufacture the newly invented shoe, the operating parts being shown in their shoe-forming positions.

Fig. 2 is a side view of the unfinished shoe produced by the machine shown in Fig. 1.

Fig. 3 is a side view of the same shoe completed.

Fig. 4 is a side view of the shoe shown in Fig. 3 with the addition of a supplementary sole.

Fig. 5 is a plan view of the shoe shown in Fig. 4.

Any suitable machine may be employed to perform the various operations whereby this newly invented shoe is made, and therefore the machine shown in Fig. 1 is only typical of the kinds of machines which may be employed in the manufacture of the new shoe. In Fig. 1 there is provided a female die 1 of suitable material such as zinc or the like mounted in a base 2 provided with a mold cavity 3 having an undercut toe portion 4 adapted to receive a toe portion 5 of a male die which is formed of sections 6, 7, the section 6 being provided with the toe portion 5 and the section 7 forming the curved heel portion that fits 45 in the undercut heel portion 7' of the female die. The die sections 6, 7 are provided with complementary inclined faces 8, 9 respectively adapted to seat against one another when the die 6, 7 is in the shoe-forming position, the section 7 being provided with a tongue 10 designed to engage a

groove 11 in the face 8 of the section 6 so as to prevent the section 7 from sliding relative to said section 6 when the sections are inserted in the die 1 and pressure is applied 60 to said die sections.

The die sections 6, 7 are loosely and yieldingly connected to one another by a loose connection such as a coil spring 12 fastened at its opposite ends to said sections respectively and designed to seat in recesses 12', 12" cut into the faces 8, 9 respectively.

The die 1 is provided with a top flat flange-forming face 13 having a groove 14 extending around the mouth of the cavity 70 3. Above the flat top face 13 of the die 1, there is provided a presser foot 15 having a bead 16 complementary to the groove 14, said presser foot being reciprocative on guide rods 18 mounted on the die 1 and projecting upward therefrom.

The presser foot 15 is provided with upwardly projecting ears 19 fastened by rivets 20 or equivalent to the lower ends of diagonally extending guide rods 21 on which is 80 reciprocatively mounted a follower 22 having ears 23 provided with perforations 24, through which said rods 21 extend. The follower 22 is pivoted at 25 to the upper end of a swinging arm 26 which is pivoted 85 at 27 to a link 28 secured by a cap screw 29, or equivalent, to the die section 7.

The follower 22 is normally supported, relative to the presser foot 15 in the position shown in Fig. 2, by coil springs 30 surrounding the rods 21 between the ears 23 and abutments 31 projecting from the guide rods 21.

The male die 6, 7 and the parts moving therewith may be operated by any suitable power and in the instance shown in the drawings said power may be applied through an arm 32 pivoted by the pivot 25 to the follower 22.

The presser foot 15 is provided with a 100 rearwardly and upwardly inclined face 33 forming a rest and guide along which the male die slides when said die is moved up and down.

In practice to make the shoe shown at a, 105 Fig. 3, the machine described above will be operated as follows: Assuming at the start that the parts are in the positions they occupy when the male die is withdrawn, a piece of leather, which may have been previously soaked in water, if desired, will be placed on the flange-forming face 13 and

the arm 32 will be operated to lower the presser foot 15 on to the leather to hold said leather in position. Then the lever 32 will be operated still further to depress the follower 22 against the expansive force of the springs 30 to force the male die 6, 7 into the shoe-forming position as in Fig. 1, thereby pressing the leather into the desired shape determined by the form of the dies so as to form the upper *b* and sole *c* all from the single piece of leather.

Then the arm 32 will be operated to raise the follower 22 or allow said follower to be forced upward by the expansive action of the springs 30, the first portion of said movement, owing to the sectional construction of the male die and to the loose connection between said sections, raising the section 7 and sliding said section forward relative to the section 6 so as to withdraw the rear face of said section 7 out of the undercut heel portion 7'; and further movement of the arm 32, by reason of the spring 12, withdrawing the toe section 6 from the undercut toe-forming portion 4 and at the same time raising the presser foot 15 out of engagement with the flange *d* of the shoe, so that the parts again assume the retracted positions.

To complete the shoe formed as above, all that is necessary is to trim it by cutting off all or part of the flange *d* and, if desired, the upper may also be provided with a slit *e* of which the edges may be drawn toward one another by laces or equivalents, not shown.

Thus it is seen that the finished shoe is

formed of a single piece of leather and is absolutely seamless.

If it is desired to have a shoe with a heavier sole, a sole *f* may be fastened to the sole *c* as in Fig. 4.

I am not aware that a seamless shoe formed of a single piece of molded leather has ever been known before this invention thereof, and the foregoing read in connection with the drawings filed herewith will enable those skilled in the art to which this invention pertains to make and use said invention.

50

I claim:

1. The method of making a shoe, which consists in holding the marginal portions of a piece of leather, and while said leather is so held producing pressure in various directions against the middle portion of said leather to form the toe and heel portions of an upper and sole.

2. The method of making a shoe, which consists in holding the marginal portions of a piece of leather, while said leather is so held pressing another portion of said leather first downward and then forward to form the toe portion of an upper and sole, pressing another portion of said leather downward to form the heel portion of an upper and sole, and then slitting the portion of said upper above the toe portion.

Signed at Los Angeles, California, this 25th day of January, 1917.

SAMUEL STRAUSS.
